UNITED STATES PATENT OFFICE.

HENDRIK J. VAN DER BIJL, OF NEW YORK, N. Y., ASSIGNOR TO WESTERN ELECTRIC COMPANY, INCORPORATED, OF NEW YORK, N. Y., A CORPORATION OF NEW YORK.

TRANSMISSION SYSTEM.

Application filed September 30, 1918. Serial No. 256,239.

To all whom it may concern:

Be it known that I, HENDRIK J. VAN DER BIJL, a subject of the King of Great Britain, residing at New York, in the county of New York, State of New York, have invented certain new and useful Improvements in Transmission Systems, of which the following is a full, clear, concise, and exact description.

- 10 This invention relates to a system for the transmission of signals and apparatus necessary thereto. It has for its object to provide a new and improved system whereby weak signal currents received at a station may be 15 suitably transformed to a value sufficient to operate a receiving instrument. In order that this instrument may be operated, even though weak signal currents are received, an amplifying device, preferably a vacuum 20 tube amplifier, is interposed between the receiving instrument and the source of reception of weak signal currents. There is also interposed between the amplifying device and the receiving instrument a controlling 25 device permitting the flow of current in one direction, and which requires, in order that current shall flow through it, that a potential exceeding a certain predetermined value shall be applied to it. Normally a local 30 source of current is applied to this controlling device which is of such value as to be slightly insufficient to establish a current through said device of the strength necessary to operate the receiving instrument. 35 When, however, weak signal currents are received and amplified, the voltage effect of these currents added to that already established by the local source upon the controlling device, will cause a current of the 40 proper value to flow through the receiver. This current controlling device may be a cold electrode gap of the proper dimensions, e. g., mercury and iron electrodes, and having applied thereto a potential from a local 45 battery, so that normally the potential across the gap is insufficient to start an arc, which arc, however, is started whenever the potential effect of the signaling currents is added to that already applied. When the effect of 50 the weak signaling currents is removed, the arc is stopped because the local potential is not large enough to maintain it. The current controlling device may also be a two-electrode thermionic device comprising a 55 heated filament and having a potential ap-

plied thereto of a value sufficient only to establish a current slightly below the value of that required to operate the receiver. In this case, when the signal current effects are added to those established, the sum of the 60 two is of a value sufficient to operate the receiver. The invention as illustrated in the figure comprises a line 1, which may be an ordinary telegraph line or may be connected to a suitable antenna (not shown) for the 65 reception of wireless signals. This line is connected to a receiving station by means of a transformer 2. In this receiving station is a vacuum tube amplifying device 3 of suitable form, comprising one or more tubes. 70 In circuit with this vacuum tube amplifying device is a receiving instrument 4 shown in the form of a line relay, and interposed between this receiving instrument 4 and the vacuum tube amplifying device 3 is a current controlling device 5, which in the form shown is a thermionic device having a heated filament 6 and an electrode 7. Supplied between these electrodes from a battery 8 is a source of potential so arranged as to make the electrode 7 positive with respect to the filament 6, and of such value as to cause a thermionic current to flow between said filament and electrode, and of a value slightly below that 80 necessary to operate the receiving instrument 4. Upon the reception of signaling currents from line 1, and their amplification in the vacuum tube 3, the voltage across the filament and electrode 7 is increased and the current therethrough is correspondingly increased to such a value as would cause the 85 operation of receiver 4.

A cold electrode gap (not shown) may be 90 substituted for the thermionic device 5, without departing from the spirit of the invention. In such a case the potential of battery 8 is of a value slightly below that required to maintain an arc across the gap, which arc however is established whenever signaling currents are received and amplified. The arc when established causes a unidirectional 95 current of the proper value to flow through the receiver 4 and operate it. When the signals cease, however, the arc is quenched because the potential remaining across the gap is insufficient to maintain the arc.

What is claimed is:

1. In a signaling system, a source of weak variable signal current, a receiver adapted 110

to be actuated by signal currents of a pre-determined value, a three electrode vacuum tube amplifying device between said receiver and said source, a gap in series with said receiver, and a source of potential applied to said gap of a value below that required to establish a space current across said gap of sufficient value to operate the receiver.

2. In a signaling system, a source of weak variable signal current, a receiver adapted to be actuated by signal currents of a pre-determined value, a three electrode vacuum tube amplifier conductively connected to said receiver and said source, a thermionic device serially interposed between said receiver and said vacuum tube amplifier, and a source of potential in circuit with said thermionic device of a value slightly insufficient to establish in said circuit current necessary to operate the receiver.

3. In a signaling system, a source of weak variable signal current, a three-electrode vacuum tube for amplifying said current, a signal-indicating device, and a unidirectional current device in series with said amplifying device and said signal-indicating device.

4. In a signaling system, a receiver, a source of local current applied to said receiver slightly insufficient to cause its operation, a thermionic device in series with the receiver, a source of weak variable signal currents, a three-electrode vacuum tube amplifier conductively connected to said receiver and said source of signal currents, said receiver operating under the cumulative current action.

5. In a signaling system, a receiver, a source of local current applied to said receiver, slightly insufficient to cause its operation, a two-electrode thermionic device in series with the receiver, a source of weak variable signal currents, a three-electrode vacuum tube amplifier conductively connected to said receiver and said source of signal currents, said receiver operating under the cumulative current action.

6. In a signaling system, a source of weak variable signal current, a receiver adapted to be actuated by signal currents of a pre-determined value, a three-electrode vacuum tube amplifying device between said receiver and said source, a gap in circuit with said receiver, and a source of potential applied to said gap of a value below that required to establish current saturation in said gap and below that required to establish a space current across said gap of sufficient value to operate the receiver.

60 7. A system comprising a vacuum tube

having an anode, a cathode and a control electrode, a unidirectional current conducting thermionic device of the two electrode type, means whereby the current through said device is varied in accordance with variations in the space current of said vacuum tube, and a circuit interrupting device actuated by the space current of said two-electrode device.

8. A system comprising a vacuum tube having an anode, a cathode and a control electrode, a unidirectional current device, means whereby the current through said device is varied in accordance with variations in the space current of said vacuum tube, and an electromagnetic circuit interrupting device having a winding in series with said unidirectional current device.

9. A system comprising a vacuum tube having an anode, a cathode and a control electrode, a two-electrode thermionic device for transmitting current waves of one sign produced from said tube, means whereby the space current of said thermionic device is varied in accordance with variations in the space current of said vacuum tube, and an electromagnetic circuit interrupting device having a winding in series with said thermionic device, said means including a lead connecting the cathode of one of said tubes to the anode of the other of said tubes.

10. A system comprising a source of alternating current, a three-electrode amplifier therefor, a unidirectional current conducting device, a circuit interrupter having an actuating winding, and means whereby said amplifier and said unidirectional current device jointly control said circuit interrupter, said means including leads connecting said winding in series with said rectifier.

100 11. A system comprising a three-electrode thermionic tube, a unidirectional thermionic current conducting device of the two-electrode type, a circuit interrupter having a winding in series with said two-electrode device, and connections for causing the space current of said two-electrode device to vary in accordance with variations in the space current of said three-electrode tube, said relay being designed to have its armature remain in one position when the space current of said three-electrode tube is at its normal value and to be operated to its other position when the space current of said first vacuum tube increases to a predetermined value.

110 In witness whereof, I hereunto subscribe my name this 25th day of September A. D., 1918.

HENDRIK J. VAN DER BIJL.
